DESIGN FOR A PENCIL

William Daneke, Linden, N. J., assignor to Joseph Dixon Crucible Company, Jersey City, N. J., a corporation of New Jersey

Application May 18, 1940, Serial No. 92,459

Term of patent 14 years

To all whom it may concern:

Be it known, that I, William Daneke, a citizen of the United States and a resident of Linden, in the county of Union and State of New Jersey, have invented a new, original, and ornamental Design for a Pencil, of which the following is a specification, reference being had to the accompanying drawing, forming a part thereof and in which the figure is a perspective view of a pencil embodying my new design.

I claim:

The ornamental design for a pencil, as shown.

WILLIAM DANEKE.
